UNITED STATES PATENT OFFICE.

HAROLD A. DENMIRE, OF AKRON, OHIO, ASSIGNOR TO THE GENERAL TIRE & RUBBER COMPANY, OF AKRON, OHIO, A CORPORATION OF OHIO.

BOX-MAKING MACHINE.

1,391,669.

Specification of Letters Patent. Patented Sept. 27, 1921.

Application filed April 9, 1920. Serial No. 372,624.

To all whom it may concern:

Be it known that I, HAROLD A. DENMIRE, a citizen of the United States, residing at Akron, in the county of Summit and State 5 of Ohio, have invented a certain new and useful improvement in Box-Making Machines, of which the following is a full, clear, and exact description.

This machine is constructed for making 10 boxes out of cardboard blanks, like that which is shown in Figure 2; and in order to understand the machine as shown and described herein it is desirable to first consider the construction and shape of these 15 box blanks.

Each blank comprises a rectangular portion *a* which becomes the bottom of the box; the integral side flaps *b*, *b*, which become the sides of the box, and the integral end flaps 20 *c*, which become the outside end members of the finished box. At each end of each side flap the blank is formed with a flap *d* the length of which is slightly less than one-half the width of the box. The two flaps *d* 25 adjacent an end of the blank are to be folded so that, in the finished box, they lie inside of the outside end flaps *c*. The blank is scored around the bottom portion *a* so that the flaps will certainly bend along the 30 lines which mark the outlines of the bottom member; and the blank is also scored along the lines on which the inside end flaps *d* must be bent out of the plane of the side flaps *b*; and a narrow strip of the cardboard 35 is cut from between the flaps *d* and *c*, whereby they are disconnected and the notches *g* are formed between them.

The machine shown is organized so that it 40 will bend the side flaps up into positions at right angles to the bottom, and will bend the inside end flaps toward each other at each 45 end of the box, and into positions at right angles to both the bottom and sides; will apply glue to the upper surfaces of the outside end flaps *c*, and will bend those end flaps up outside of and into contact with the inside flaps and will press and hold the glued surfaces in contact until the glue sets.

The invention consists in the construction 50 and combination of parts by which the boxes are made into blanks as described, all as herein shown and hereinafter described and definitely pointed out in the appended claims.

55 In the drawing, Fig. 1 is a sectional plan

view of the machine, the section being in the plane of line 1—1 on Fig. 4; Fig. 2 is a plan view of the bed of the machine with a blank resting thereon in position to be folded up when the plunger descends; Fig. 3 is a 60 sectional side elevation in the plane indicated by the line 3—3 on Fig. 1; Fig. 4 is a sectional end elevation in the plane of line 4—4 on Fig. 1. Fig. 5 is a perspective view of one end of a partly formed box, this view 65 showing the position which the different parts of the blank will assume at one stage of the bending process performed by the machine.

Referring to the parts by reference characters, 10 represents the horizontal main bed plate through which is a rectangular vertical hole 12 in which the folded up box fits slidably but snugly. A rectangular tube 11 of the same internal dimensions as the 70 hole 12, is secured to the bed plate in registering relation to said hole and extends down therefrom, so as to form a chute down which the finished boxes are forced, as, one by one 75 they are pushed down through said hole. 80

30 represents a vertically reciprocating rectangular plunger of slightly smaller dimensions than the hole 12 so that it and a folded up box may descend into said hole.

The plunger is located over the hole 12, so 85 that on its down stroke it will enter the hole carrying with it the box made by folding one of the described box blanks. Any suitable means may be employed to impart to this plunger its vertical and properly guided reciprocating movement. For example, a shaft 31 may be rotatably mounted upon the frame member 32; a crank 33 may be fixed to this shaft; and this crank may be connected by a connecting rod 34 with the plunger. Vertical guide rods 35 carried by the plunger 90 may slidably fit in vertical sleeves 36 which are fixed to the frame of the machine.

Upon the bed plate adjacent the four corners of the hole 12 are four blank supporting and flap bending blocks 19, the upper surfaces of which are all in the same plane, a slight distance, say half an inch, above the top of the bed plate.

These blocks 19 are so placed that they 105 engage beneath the inside end flaps *d* but do not project beneath the side flaps *b*, nor the outside end flaps *c* of the blank in the machine. It is desirable that these blocks be very close to the corners of the rectangular 110

lar hole; and in the best construction, as shown, these blocks have one vertical wall 19^a which is in substantially the same vertical plane as the adjacent end wall of the 5 hole 12; and another vertical wall 19^b which is in substantially the same vertical plane as the adjacent side wall of said hole 12. The line in which the two vertical walls 19^a, 19^b, intersect is in substantial alinement with 10 the line in which the adjacent end and side walls of the hole 12 intersect.

The blanks are not usually stiff enough to maintain their shape when supported by these flaps only; and therefore it is desirable 15 that other blank supporting platforms be provided adjacent the two sides and ends of the hole. As shown the blocks or platforms 15, 16, are secured on the bed plate a slight distance away from the two sides respectively of the hole 12, but with their edges parallel with said sides; and these platforms are in such position that a part, say about one-half of each of the side flaps *b*, are respectively supported by these two platforms. At the ends of the hole are two other blank supporting platforms 17, 18, the edges of which are set back a slight distance from the ends of the hole, and these platforms are so placed that rather more 30 than half the end flaps *c* will be supported upon them when the blank is put into the machine.

Two receptacles 40 for containing liquid glue are suspended from the machine frame 35 adjacent the ends of said hole and over the bed plate. Each of these is provided with two drip pipes 41, the lower discharge ends of which are so placed that they will drip glue on the upper faces of the end flaps *c* 40 when a blank is in the machine. Below these drip pipes holes 13 are formed through the platforms 17, 18, and through the bed plate, so that the glue will drop through these holes when a blank is not in the 45 machine. Below these holes are receptacles 45 for catching the glue which flows from the drip pipes through these holes.

Near each end of the bed plate a guide and stop block 50 is fixedly secured. These stop 50 blocks are above the planes of the platforms 17, 18. The vertical edges 51 of these blocks which face the ends of the hole 12, serve as guides to aid in properly placing the blanks in the machine, the ends of the outside end flaps *c* being in substantial engagement with these edges. On these blocks also are stop shoulders 52 against which the rear edges 55 of the flaps *c* engage whereby the blanks are stopped in the proper position.

60 In utilizing the machine for the stated purpose, a blank is put into the machine, and it is readily placed in the proper position by causing the ends of the outside end flaps to pass between the vertical faces 51 65 of the two guide blocks 50, and until the

rear edges of said flaps come into engagement with the shoulders 52 on said guide blocks. When the blank is in this position the glue drips slowly onto the upper faces of the outside end flaps *c*, *c*. The plunger 70 immediately comes down, forcing the bottom of the blank downward. The inside end flaps *d*, *d*, being supported on the bending blocks 19, can not move down with the bottom portion of the box, and therefore 75 these end flaps are bent up out of the plane of the side flaps of which they are parts. The side flaps *b*, *b*, and the outside end flaps *c*, *c*, are not so rapidly bent up. Therefore, when they are bent up,—as they will be as 80 the plunger descends,—the outside end flaps *c*, *c*, will overlie the inside end flaps *d*, *d*; and the bending up of the outside end flaps will aid in bending the inside end flaps into the stated final positions. When the blank 85 has been carried by the plunger down into the hole 12 these various flaps will have been bent to the position shown, and the glue coated faces of the outside end flaps will be pressed against the adjacent faces of the inside end flaps. When the plunger is withdrawn this finished box is left in the chute referred to. When another similarly bent blank is pushed down through the hole it engages the top of the previously formed box 90 and pushes it down through the chute; these operations are continued and one by one the boxes are forced out of the lower end of the chute. This chute is, however, long enough to hold each box long enough for the glue 100 to set so as to hold the flaps in the stated relation with one another when the box is discharged.

As a precautionary expedient to insure that the outside end flaps shall not be folded 105 up in advance of the inside end flaps, the blocks 50 are provided with flanges 56 which extend therefrom toward the hole 12 and slightly overhang the edges of the outside end flaps *c*. These flanges 56 will, when the 110 plunger begins to descend, and when therefore the flaps begin to bend, prevent the outside end flaps from bending up until after the corners of the end flaps have been bent so as to overlie the outside end flaps. 115

Having described my invention, I claim:—

1. In a box making machine, the combination of a bed plate having a rectangular hole therethrough, and four immovable blank supporting flap bending blocks secured upon said bed plate adjacent the four corners of said rectangular hole and in position such that they will engage with and support only the inside end flaps of the described box blank when said blank is in position to be 120 operated upon by the machine, and a vertically reciprocating plunger for forcing the box blanks down into said hole and thereby causing the flaps to be bent into positions substantially as herein described. 125

2. In a box making machine, the combination of a bed plate having a rectangular hole therethrough, and four immovable blank supporting flap bending blocks secured upon said bed plate adjacent the four corners of said rectangular hole and in position such that they will engage with and support only the inside end flaps of the described box blank when said blank is in position to be operated upon by the machine, said blank supporting and flap bending blocks having one vertical wall which is in substantially the same vertical plane as the end wall of said rectangular hole and having another vertical wall which is in substantially the same vertical plane as the adjacent side wall of said rectangular hole,—said surfaces meeting in a line which is substantially coincident with the line in which the adjacent side wall and end wall of said rectangular hole meet.
3. In a box making machine, the combination of a bed plate having a rectangular hole therethrough, and four immovable blank supporting flap bending blocks secured upon said bed plate adjacent the four corners of said rectangular hole and in position such that they will engage with and support only the inside end flaps of the described box blank when said blank is in position to be operated upon by the machine, a vertically reciprocating plunger for forcing the box blanks down into said hole and thereby causing the flaps to be bent into position substantially as herein described, and immovable means located over the outside end flaps for dripping glue onto the upper surfaces of the outside end flaps of said blank while the blank is in the machine.
4. In a box making machine, the combination of a bed plate having a rectangular hole therethrough, and four immovable blank supporting flap bending blocks secured upon said bed plate adjacent the four corners of said rectangular hole and in position such that they will engage with and support only the inside end flaps of the described box blank when said blank is in position to be operated upon by the machine, a vertically reciprocating plunger for forcing the box blanks down into said hole and thereby causing the flaps to be bent into position substantially as herein described, means located over the outside end flaps for discharging glue onto the upper surfaces of the outside end flaps of said blank while the blank is in the machine, and a rectangular chute whose dimensions are substantially the same as the dimensions of the rectangular hole, said chute being secured in position to form a downward continuation of said hole.
5. In a box making machine, the combination of a bed plate having a rectangular hole therethrough, and four blank supporting flap bending blocks secured upon said bed plate adjacent the four corners of said rectangular hole and in position such that they will engage with and support only the inside end flaps of the described box blank when said blank is in position to be operated upon by the machine, said blank supporting and flap bending blocks having one vertical wall which is in substantially the same vertical plane as the end wall of said rectangular hole and having another vertical wall which is in substantially the same vertical plane as the adjacent side wall of said rectangular hole, two platforms located respectively in front of and behind said rectangular hole, and a short distance back from the edges thereof and in position to support the side flaps of said blanks.
6. In a box making machine, the combination of a bed plate having a rectangular hole therethrough, and four immovable blank supporting flap bending blocks secured upon said bed plate adjacent the four corners of said rectangular hole and in position such that they will engage with and support only the inside end flaps of the described box blank when said blank is in position to be operated upon by the machine,—said blank supporting and flap bending blocks having one vertical wall which is in substantially the same vertical plane as the end wall of said rectangular hole and having another vertical wall which is in substantially the same vertical plane as the adjacent side wall of said rectangular hole, two platforms located respectively in front of and behind said rectangular hole, and a short distance back from the edges thereof and in position to support the side flaps of said blanks.
7. In a box making machine, the combination of a bed plate having a rectangular hole therethrough, and four immovable blank supporting flap bending blocks secured upon said bed plate adjacent the four corners of said rectangular hole and in position such that they will engage with and support only the inside end flaps of the described box blank when said blank is in position to be operated upon by the machine,—said blank supporting and flap bending blocks having one vertical wall which is in substantially the same vertical plane as the end wall of said rectangular hole and having another vertical wall which is in substantially the same vertical plane as the adjacent side wall of said rectangular hole, two platforms located respectively in front of and behind said rectangular hole and a short distance back from the edges thereof and in position to support the side flaps of said blanks, there being also platforms adjacent the ends of said rectangular hole set back a short distance therefrom for supporting the outside end flaps of said blank.
8. In a box making machine, the combination of a bed plate having a rectangular hole

therethrough, and four blank supporting flap bending blocks secured upon said bed plate adjacent the four corners of said rectangular hole and in position such that they 5 will engage with and support only the inside end flaps of the described box blank when said blank is in position to be operated upon by the machine,—said blank supporting and flap bending blocks having one vertical wall 10 which is in substantially the same vertical plane as the end wall of said rectangular hole and having another vertical wall which is in substantially the same vertical plane

as the adjacent side wall of said rectangular hole, two platforms located respectively in 15 front of and behind said rectangular hole, and a short distance back from the edges thereof and in position to support the side flaps of said blanks, the pair of blocks adjacent each end of said rectangular hole 20 being adjustable toward and from each other.

In testimony whereof I hereunto affix my signature.

HAROLD A. DENMIRE.
